ELECTRICAL RESISTANCE HEATER ROLLER CONTACT UNIT

Edgar A. Ellinghausen, 418 W. Clarendon, Prospect
Heights, Ill. 60070

Filed Apr. 11, 1966, Ser. No. 1,884

Term of patent 14 years

(Cl. D26—1)

FIG. 2

FIG. 3

FIGURE 1 is a front perspective view of an electrical resistance heater roller contact unit showing my new design;

FIGURE 2 is a side elevational view thereof; and
FIGURE 3 is a rear elevational view thereof.

The dominant features of my design reside in the portions shown in full lines. The conductor wire and the electrical leads are shown in broken line for illustrative purposes only.

This application is a continuation of application Ser. No. D. 84,330, filed Mar. 17, 1965, and now abandoned.

I claim:

The ornamental design for an electrical resistance heater roller contact unit, as shown and described.
